TENNIS RACKET

Percy Charles Caines, Strathfield, near Sydney,
New South Wales, AustraliaApplication October 9, 1939, Serial No. 298,649
In Australia December 1, 1938

5 Claims. (Cl. 273—73)

This invention relates to improvements in tennis rackets having tubular metal frames.

In the past it has been proposed to form metal frame tennis rackets by drilling holes for the gut in a similar manner to the drilling of holes in wooden frame rackets but this method was not satisfactory, in as much that while the outside holes took the strain of the gut, the friction of the gut on the holes on the inside of the frame, caused by the continual flexing of the racket in play, subsequently frayed and severed the gut at these points.

An object of the present invention is to overcome the above disadvantage and to provide a metal frame racket of simple yet robust construction.

According to the present invention a metal tube of suitable cross section and length is filled with sand and bent to the shape of a tennis racket in such a manner that the two ends of the tube form part of the handle when welded or secured together. A bridge piece is then welded between the converging ends to form the complete oval shape of the frame.

The frame thus formed has recessed portions stamped on its inner face at predetermined intervals and extending between each recessed portion is a channel, the length of which is governed by the spacing of the racket strings. This channel is cut between the adjacent recessed portions and runs longitudinally with respect to the frame. The punched depressed portion does not remove the metal but merely displaces it inwardly and in so doing, by the nature of the punch, forms an internal guiding recess for the gut to rest upon inside the tubular frame.

In order that the invention may be more readily understood reference will now be made to the accompanying drawing wherein:

Fig. 1 is a front elevation of the improved metal frame racket constructed in accordance with the present invention.

Fig. 2 is an enlarged fragmentary detail view of a portion of the frame.

Fig. 3 is a transverse section on the line 3—3 of Fig. 2.

Fig. 4 is a transverse section on the line 4—4 of Fig. 1 while

Fig. 5 is an enlarged fragmentary detail view in plan of one of the channels in the frame showing the filler piece or bar for preventing the finishing or commencing knots from sliding through said channels.

The frame 6 comprises a metal tube 7 of suitable cross section and length, which having been filled

with sand, is bent to the required shape in such a manner that the two ends of the metal tube 7, form a handle 8 when securely welded together. A separate bridge piece 9 is welded between the converging ends of frame 6 just prior to formation of the throat 10 for the purpose of completing the oval head, characteristic of the tennis racket.

The handle 8 is formed by opening the respective ends of the metal tube 7 at the base of the throat 10 and welding their edges to form the said handle which has approximately twice the cross sectional area of the frame. A leather grip such as 11 may be added to prevent slipping during play.

For a short portion of its length, the metal tube 7 is left unwelded to form a longitudinal slot 12 in the handle 8, for the purpose of imparting the desired flexing to the throat zone and to eliminate any tendency of the upper portion of the handle 8 to buckle or snap when subjected to heavy play.

Referring to the enlarged portion of the frame 6 illustrated in Fig. 2 recesses 13 are stamped on the inner side thereof at predetermined intervals 25 leaving upraised portions 14. A small hole is now drilled through these upraised portions 14 said hole being expanded by a punch to form slots or channels 15 extending between adjacent recesses 13 and running longitudinally with respect to the frame.

Expansion of the hole is preferably done under heat and the metal displaced therefrom forms a raised lip 16 about the slots or channels 15. The lip 16 is curved towards the centre of the 35 said recessed portions 13 in such a manner that a smooth seat may be formed inside of the frame for the gut strings of the racket and chafing of the strings during play is entirely eliminated.

The stamped recesses 13 form suitable curved 40 seats for the strings to rest upon inside the tubular metal frame 6. If desired the formation of the recesses and channels may be produced during the act of bending the frame to the desired shape.

The racket may be strung in known manner, but owing to the displacement of the metal adjacent to the slots 15 to form the seats in the frame 6 for the strings, the knots at the end of the gut would draw through the said slots 15 50 were it not for the fact that a small metal bar or filler piece 17 (see Fig. 5) is placed in the slot 15 before the knot is tied at either the finishing or commencing points.

The present construction gives a neat appear- 55

ance to the racket and ensures that the strings do not come into contact with the ground during the time the racket is being used for playing.

I claim:

- 5 1. A tennis racket comprising a substantially oval frame of tubular metal, a two-part handle extending therefrom and having portions joined together at spaced intervals to leave a flexing zone, the inner surface of the frame having a plurality of spaced slots provided therein and also provided with a plurality of depressions alternately arranged with respect to the slots, and the surfaces of the depression on the inside of the tube constituting seats for the gut strings which are adapted to be engaged therewith after being passed through the slots.
- 10 10. A tennis racket comprising a substantially oval frame of tubular metal having a plurality of spaced slots provided at intervals in the inner surface thereof and also provided with a plurality of depressions alternately arranged with respect to the slots, and the surfaces of the depression on the inside of the tube constituting seats for the gut strings which are adapted to be engaged therewith after being passed through the slots.
- 15 15. A tennis racket comprising a substantially oval frame of tubular metal having a plurality of spaced slots provided at intervals in the inner surface thereof and also provided with a plurality of depressions alternately arranged with respect to the slots, and the surfaces of the depression on the inside of the tube constituting seats for the gut strings which are adapted to be engaged therewith after being passed through the slots.

- 20 2. A tennis racket as claimed in claim 1, in which a bridge piece is arranged between the sides of the frame adjacent the inner ends of the handle and acts to close the frame and is provided with alternate slots and recesses forming internal seats.

- 25 3. A tennis racket comprising a tubular metal frame, a tubular metal handle, a plurality of spaced depressions formed in the inner surface of the frame said depressions producing inside the tubular frame curved seats, a gut stringing engaging the curved seats, a plurality of elongated slots formed upon the inside of the frame

between the respective depressions, rounded ends for the slots, and smooth seats in the slots for the gut as it passes to and from the curved seats inside the tubular frame.

4. A tennis racket comprising a tubular metal frame, a gut stringing for the frame, said tubular metal frame having a plurality of depressed portions forming internal seats for the gut on the inside of the tubular frame, a plurality of elongated slots formed inside the frame between the depressed portions to receive the gut, the ends of the tubular frame being opened and welded to form a tubular handle, a leather strip for the handle, and a flexing zone formed by leaving portions of the handle unwelded. 15

5. A tennis racket including a substantially oval frame of tubular metal having a plurality of spaced recesses provided at intervals in the inner surface thereof to provide seats on the inside of the frame and having longitudinal slots arranged between and in alternate formation with the recesses, raised lips arranged about the slots and curved towards the center of the adjacent seats in such manner as to produce smooth seats for the gut strings of the racket where they pass 20 into and from the frame, and a handle associated with the frame. 25

PERCY CHARLES CAINES.
